UNITED STATES PATENT OFFICE.

FRANK W. VAN NESS, OF MILWAUKEE, WISCONSIN, ASSIGNOR TO FRANK J. MATCHETTE, OF MILWAUKEE, WISCONSIN.

VACUUM CLEANING-TOOL.

1,053,683.

Specification of Letters Patent. Patented Feb. 18, 1913.

Application filed May 2, 1910. Serial No. 558,814.

To all whom it may concern:

Be it known that I, FRANK W. VAN NESS, a citizen of the United States, residing at Milwaukee, in the county of Milwaukee and 5 State of Wisconsin, have invented certain new and useful Improvements in Vacuum Cleaning-Tools, of which the following is a specification, reference being had to the accompanying drawing, forming a part 10 thereof.

This invention relates to improvements in that class of vacuum cleaning tools which are intended for use in sweeping, or cleaning, uncarpeted floors of wood, tiles, etc., 15 or other hard surfaces.

The great objection to many of the hard surface sweepers in use at the present time is that they sweep the dirt before them, piling it up in a ridge or pile in front of 20 the tool, and, eventually, the tool will ride up on to and over the ridge of dirt and scrape the dirt into and over the surface or floor, thereby scratching and marring the surface besides injuring the tool. Many 25 hard surface or bare floor sweepers have their floor contacting surface made of felt or some soft polishing material, and the dirt, especially sharp grains of sand, will become embedded in such material and 30 will convert the tool into a scratching implement which will act as though its floor contacting surface were covered with sandpaper. Moreover, many of the hard surface sweepers in use at the present time 35 leave a ridge or pile of dirt in front of them at the completion of the sweeping stroke which can only be removed by turning the tool and making a sweeping stroke at right angles to the former direction of movement 40 of the tool or by using a different kind of tool.

The objects of this invention are to construct hard surface or bare floor sweepers, of the type which have a rubbing or bearing 45 surface, or surfaces, which rests directly upon a floor, so that they will not push the dirt in front of them in a ridge or pile, but will move the dirt laterally with respect to the direction of motion of the tools 50 and thereby sweep the dirt into windrows in line with air passages in the tools so that the dirt will be carried into the tools by the air rushing into and through said air passages, and generally to improve the details 55 of construction of such tools in the man-

ner to be more specifically described hereafter.

The principal object of this invention is realized by providing the floor contacting surfaces of bare floor sweepers with a plurality of V-shaped grooves which have their wide parts located at the sweeping sides of the tools and which have air passages at their vertices. Preferably these V-shaped grooves are separated from adjacent grooves 60 by triangular-shaped polishing members provided with substantially sharp apexes on the sweeping sides of the tools. The sides of the V-shaped grooves are preferably substantially perpendicular to the sweeping 65 faces of the tools so as to have no tendency to roll the dirt under the polishing faces of the tools.

Referring to the drawings which accompany this specification and for a part thereof, on which drawings the same reference characters are used to designate the same elements wherever they may appear in each of the several views, and which drawings illustrate an embodiment of this invention, 70 Figure 1 is a bottom plan view of a tool; Fig. 2 is a transverse vertical section of the tool and handle taken on the line *a—a*, Fig. 1, looking in the direction indicated by the arrows; and Fig. 3 is an elevation of a part 75 of the tool.

Referring specifically to the drawings, the reference numeral 1 designates a plate to which a hollow socket member 2 is pivotally secured, so that said socket member 90 2 can be swung up and down with respect to plate 1. In the specific structure shown by the drawings, a retaining member 3 is secured to plate 1 and this retaining member has downwardly projecting and inturned 95 edges or flanges 4 and 5, for a purpose to be hereinafter described. The retaining member 3 has secured thereto other retaining members 6, 6, which are provided with downwardly extending and outwardly bent 100 edges or flanges 7 and 8, so as to form wedge-shaped spaces between the flanges 4 and 8 and 5 and 7.

The numerals 9 and 10 respectively, designate two removable members, which may be made of wood or any preferred material, with upwardly and outwardly flaring edges which are adapted to be received within flanges 5 and 7 and 4 and 8 respectively and are securely but removably held to the re- 105 110

taining members 3 and 6 by the flared flanges thereof, as is clearly shown by Fig. 2 of the drawings.

It is preferred to secure triangular-shaped pieces of felt, or other polishing material, designated by the common reference numeral 11, to the underside of removable members 9 and 10 to form V-shaped grooves *h* on the floor contacting face of the tool, and these triangular-shaped members 11 are not in contact at their bases, but are separated slightly so as to provide air passages 12, which are in communication with a slot 13 extending nearly the length of the tool. The slot 13 is in communication by means of an aperture 14 in the retaining member 3 with a slot 15 in the plate 1, whereby free communication is established between the air passages 12 and slot 13 with the hollow interior of the socket member 2 with which a tubular handle 16 may be connected.

The removable members 9 and 10 are slideable endwise with respect to the retaining members 3 and 6 and between the flanges 5 and 7 and 4 and 8 respectively, so as to be removable therefrom and when they are inserted and are in their determined position therein, they are retained against endwise movement by vertically movable pins 17 and 18, which drop into recesses 19 and 20 in members 9 and 10.

The longitudinal slot 13 is formed by the flanges 7 and 8 and by the bases or inner ends of the triangular-shaped pieces 11 which do not extend inwardly beyond the edges of the sweeping members 9 and 10 to which they are secured. In order to partially close the ends of slot 13 one end of member 9 and one end of member 10 projects across the full width of the slot and terminates in a straight edge parallel with the farther extremity of the slot, as shown by the lines designated by the reference character 21 and the reference character 22.

The end members corresponding to the triangular-shaped members 11 on one end of members 9 and 10 are shaped like right angle triangles, as clearly shown by Fig. 1 of the drawings, and these members are designated by the reference characters 23 and 24 respectively. The triangular members corresponding to triangular members 11 on the opposite ends of members 9 and 10 are constructed of a generally triangular outline, but with an additional triangular part added to the pieces of the triangles so that air passages 25 and 26, (of substantially the same size as air passages 12) and V-shaped grooves *h* are provided at the ends of slot 13 by the co-action of small triangular pieces 27 and 28, as will be readily understood from an inspection of Fig. 1 of the drawings.

It will be readily seen from an inspection 65 of the drawings that by lifting pins 17 and

18 the removable members 10 and 9 can be slid endwise and removed from the retaining members 3 and 6 by sliding member 9 to the left and member 10 to the right (looking at Fig. 1 of the drawings).

The function and operation of the tool is as follows: When the tool is moved either forward or backward over the floor, the dust and dirt are swept sidewise, with respect to the direction of motion of the tool, by the triangular-shaped members 11 and is piled up into windrows opposite air passages 12 and the air flowing in through air passages 12 takes all the dust and dirt with it. Moreover, the action of the tool disclosed by the drawings and described in this specification is to move the dust away from the path of movement of the felt or polishing members 11, 23, 24, 27 and 28, so that these felt members pass over a cleaned surface and serve to polish that surface, and the air entering the V-shaped grooves *h* and air passages 25 and 26 at the ends of the tool carries with it the dust and dirt for some little distance from the ends of the tool.

What is claimed is:

1. The combination, in a vacuum cleaning tool, of a plate, having a slot for the outward passage of dust-laden air, and members secured to the bottom of the plate and separated to form an elongated slot in communication with the slot in the plate, the floor-contacting parts of said members being composed of a plurality of triangular-shaped members separated from each other to form V-shaped grooves which are in open communication at their apexes with said elongated slot.

2. The combination, in a vacuum cleaning tool, of a plate, having a slot for the outward passage of dust-laden air, provided with downwardly projecting and inwardly and outwardly turned flanges, and removable members slidably engaged with and held by said flanges, the floor-contacting parts of said members comprising a plurality of triangular-shaped members separated from each other and forming therebetween a plurality of V-shaped grooves which are in open communication at their apexes with an elongated slot formed between the bases of said triangular-shaped members.

3. The combination, in a vacuum cleaning tool, of a plate, having a slot for the outward passage of dust-laden air, provided with downwardly projecting and inwardly and outwardly turned flanges, and removable members slidably engaged with and held by said flanges and separated from each other but provided at opposite ends with parts which project toward and terminate at the other removable member.

4. The combination, in a vacuum cleaning

tool, of a plate, having a slot for the outward passage of dust-laden air, retaining members provided with downwardly projecting and inwardly and outwardly turned flanges, removable members, separated from each other except at their ends, slidably engaged with and held by said flanges, means for locking said plate and said removable members together, and a plurality of triangular-shaped members secured to the bottoms of said removable members and separated from each other to form an elongated slot between their bases and a plurality of V-shaped grooves which are in open communication at their apexes with 15 said elongated slot.

In witness whereof I hereto affix my signature in presence of two witnesses.
